Primary Examiner — Cynthia Ramirez*Assistant Examiner* — Llorellys Martinez-Rivera(74) *Attorney, Agent, or Firm* — Thomas, Karceski & Karmilovich, P.C.(57) **CLAIM**

The ornamental design for a dual lit grab rail, as shown and described.

DESCRIPTION

FIG. 1 is a perspective view of a dual lit grab rail showing our new design;

FIG. 2 is a right side view thereof;

FIG. 3 is a left side view thereof;

FIG. 4 is a top plan view thereof;

FIG. 5 is a bottom plan view thereof;

FIG. 6 is an end view thereof;

FIG. 7 is an opposite end view thereof; and,

FIG. 8 is a perspective view of the dual lit grab rail, in an environment of use.

The broken lines shown in FIGS. 1-8 illustrate portions of the dual lit grab rail which do not form part of the claimed design. The dual lit grab rail is shown with a symbolic break in its length. The appearance of any portion of the article between the break lines forms no portion of the claimed design.
